UNITED STATES PATENT OFFICE.

FREDERICK W. ROBERTSHAW, OF PITTSBURGH, PENNSYLVANIA

TANK-VALVE.

1,125,596.

Specification of Letters Patent. Patented Jan. 19, 1915.

Application filed February 28, 1914. Serial No. 821,822.

To all whom it may concern:

Be it known that I, FREDERICK W. ROBERTSHAW, a citizen of the United States, residing at Pittsburgh, in the county of Allegheny and State of Pennsylvania, have invented a new and useful Improvement in Tank-Valves, of which the following is a full, clear, and exact description, reference being had to the accompanying drawings, forming part of this specification, in which—

Figure 1 is a side elevation of a valve embodying my invention; Fig. 2 is a view of the same partly in side elevation and partly in vertical section; Fig. 3 is a section on the irregular line III—III of Fig. 1; and Fig. 4 is a section on the line IV—IV of Fig. 2.

My invention has relation to tank valves, and more particularly to valves of the general character described and claimed in Patent No. 864,262, granted to F. S. McTighe and myself on August 27, 1907.

The object of the present invention is to so construct a valve device of the general character of that in the said patent, as to permit of ready inspection of the movable valve member at all times, without the necessity for dismantling; also to improve the construction and arrangement of the upper portion of the valve member and its packing; and also to improve the construction of the valve device in other respects as will hereinafter more fully appear.

The nature of the present invention will be best understood by reference to the accompanying drawings, in which I have shown the preferred embodiment thereof and which will now be described, it being premised, however, that various changes may be made in the details of construction and arrangement of the parts, without departing from the spirit and scope of my invention as defined in the appended claims. In these drawings, the numeral 2 designates the usual tail piece, to which the water supply pipe (not shown) is connected and which is provided with the usual jam nut 3, for securing the valve in place in the bottom of a float tank as in the said patent. Secured to or formed integrally with this tail piece is a valve casing which comprises a lower portion 4, and an upper portion 5. These two portions are separated from each other vertically by the free space 6 and are connected only by the laterally offset yoke

arms 7. The vertically movable valve member has a lower cylindrical portion 8, which has a neat bearing fit in the opening 9 in the top wall of the lower casing portion 4. The lower end of this portion 8 is adapted to close on the valve seat 10, which surrounds the port or passage 11, which leads from the tail pipe into the interior discharge chamber 12 of said casing portion. The seating face of the valve member is preferably provided with a washer 13, secured by a screw 14.

Within the open space 6 between the upper and lower casing portions 4 and 5, the valve member has a reduced portion 15, between the portion 8 and the collar 16. This reduced portion is engaged by the bifurcated end portion 17 of the usual float lever 18, which is pivoted to one of the connecting arms 7 at 19. The upper portion of the valve member extends within the upper casing portion 5, and has secured to its upper end by a screw 20 or other suitable means a flexible cup leather 21. This upper end portion of the valve member with the cup leather forms a piston which is arranged to work within a cylinder formed by a removable screw cap 22, which is screwed into the casing portion 5. The effective pressure area of the upper end of this piston is substantially equal to the exposed area of the lower end of the valve member when the latter is seated, whereby the valve is substantially balanced, the balancing pressure in the cylinder of the cap 22 being obtained by a vertical passage 23, through the valve body, as in the patent above referred to.

In order to permit the valve and its cup leather to be readily introduced into the cylinder, the lower end of the cylinder and the interior of the upper casing portion 5 are cut out to form a bell-mouth.

The numeral 24 designates escape openings in the casing portion 4, through which the water from the tail pipe flows into the tank when the valve member is unseated. 25 designates the usual connection on the casing portion 4 for the after flow.

By separating the upper portion and lower casing portions 4 and 5 in the manner herein shown and described, the operation of the valve member can be readily inspected at any time without dismantling the valve or removing any of the parts. This consti-

tutes an important feature of advantage, since failure of devices of this kind to properly operate is usually caused by the valve member sticking either at its upper 5 or lower end portions. In the construction described, the valve member can be readily inspected and the cause of any trouble of this character quickly located. The construction also provides means whereby it 10 can be readily determined if the valve member is leaking at either end portion.

The construction at the upper end of the valve member in which the cup leather 21 is directly secured thereto, is also an important 15 improvement over the construction shown in said patent. That construction required the use of a rigid ring secured between the cap member and the upper portion of the casing and also a leather or flexible washer 20 over said ring and through which the neck of the valve member extended. Trouble was experienced in the operation of these valves, due to the difficulty of maintaining these leather washers in proper condition. 25 The present construction enables the use of a cup leather of the usual character and which will maintain itself in proper condition for a considerable length of time.

It will be noted that the present construction omits the feature of the inner series 30 of discharge openings in the lower portion of the casing, which were present in the structure of said patent and which were controlled by the lower portion of the valve 35 member, although this is not essential.

I claim:

1. A valve device of the character described, comprising a casing having upper and lower casing portions which are separated vertically from each other by laterally offset, oppositely located yoke arms, the lower casing portion having a port, and the upper casing portion having a detachable cylinder open at its lower end, and a vertically movable valve member having one end portion extending within the lower casing portion and controlling said port, and its opposite end portion extending into said cylinder and carrying a cup-leather, said upper casing portion having an enlarged 40 opening around the valve below the open end of the cylinder; substantially as described. 45

2. A valve device of the character described, comprising a lower casing portion 50 having an annular valve guide and a port below the guide, oppositely arranged yoke arms rising from said annular portion, an upper internally threaded portion carried by said arms, and a cylinder threaded into 55 said upper portion and open at its lower end, the lower end of the cylinder and said upper portion being bell-mouthed; substantially as described.

In testimony whereof, I have hereunto 60 set my hand.

FREDERICK W. ROBERTSHAW.
